SHALLOW-WATER ALARM

Peter L. Keating, Baton Rouge, La.

Application February 4, 1947, Serial No. 726,292

3 Claims. (Cl. 200—52)

1

This invention relates to devices for warning of shallow water beneath boats, the primary object of the invention is to provide a shallow water alarm which may be installed on any small boat without extensive alteration thereof and at small expense, and which is adjustable to warn of shallow bottom conditions at different depths below the boat as the boat moves through relatively shallow waters.

A further object of the invention is to provide a combined alarm and indicator of the above described character having an arm extending downwardly from the bottom of the boat to yieldably engage the water bottom therebelow, and indicating means associated with the arm to show its adjustment to operate at different depths, and alarm means for visually and audibly warning the operator of the boat whenever an unsafely shallow area has been reached.

Other objects and advantages of the invention will become apparent from the following description of a preferred embodiment thereof as illustrated in the accompanying drawings, and in which:

Figure 1 is a side elevational view of a boat showing said embodiment installed therein, partly broken away to show structure,

Figure 2 is an elevational view with the control box door open, partly broken away to show structure,

Figure 3 is a transverse vertical section taken on the line 3—3 of Figure 2,

Figure 4 is a horizontal section on an enlarged scale, taken on the line 4—4 of Figure 3,

Figure 5 is a horizontal section taken on the line 5—5 of Figure 2, and

Figure 6 is an enlarged longitudinal section taken through the lower end of the feeler rod, with the ground-engaging extension engaged therein.

Referring in detail to the drawings, in which like reference characters designate like parts throughout the several views, the numeral 9 generally designates the illustrated alarm device installed on a motor boat 10 having a hull 12 and a cabin 14, the boat being shown moving forwardly through shallow water over an irregular bottom 18.

The alarm device 9 comprises an upstanding hollow tubular housing 19 within the hull 12 having on its lower end a belled portion 20 registered with a conforming opening 22 in the hull bottom 12 to prevent entry of water into the hull through the opening 22. The upper end of the housing 19 is closed by a cap 24 rotat-

ably resting thereon and having a handle 26 and a pointer 28 integral therewith, the upper end of the housing 19 being located well above the water line 30. The handle 26 and pointer 28 are made short enough to allow them to be swung through a complete circle without interference with an object in the boat. The housing 20 is supported in position by means of a bracket 32 engaging a bulkhead 34 and encircling the housing as shown in Figure 1.

An inner tubular casing 36 having its upper end threaded into the inner recess 38 of the cap 24, extends loosely downwardly through the housing 19 and has a lateral flange 36' on its lower end, as shown in Figures 2 and 3, to engage the sides of the bell 20 and prevent the casing 36 from being drawn upwardly through the housing 19. A rod 40 extends slidably and downwardly through the cap 24, through the casing 36, and has its lower end bifurcated as indicated at 41 to receive the arched portion 44 of a feeler lever 46, to which it is pivoted by a pin 42 traversing the bifurcation, the adjacent end of the lever 46 being pivoted at 48 to one side of the bell 20 on the lower end of the housing 19. The arched portion 44 of the lever 46 moves through slots 21, 21 in the lower end of the casing 36. A ground engaging extension 50 is threaded endwise into a recess formed in the lower or outer end of the feeler lever 46 as shown in Figures 1 and 6.

The feeler lever 46 is movable through a vertical angle to bring its extension 50 into engagement with the water bottom 18 whenever less than the desired safe minimum shallowness obtains. Whenever a place is reached by the boat where less than the minimum safe shallowness obtains for which the feeler lever 46 has been adjusted, the extension 50, and hence the lever 46 are elevated and the alarm set off. The inner casing 36 is turnable on a vertical axis by means of the handle 26 for the purpose of turning the feeler lever 46 in different directions.

Within the cabin 14 a control box 52 having sidewalls 54 and a hinged door 56 is supported above the housing 19. The upper end of the rod 40 extends into the control box through its bottom 53, and has a rounded upper end 60 adapted to act as a cam to engage and displace a leaf spring contactor 62 of a switch 63 mounted on the upper end of a housing 64, when the rod 40 is elevated to its highest point indicating unsafely shallow water beneath the boat, so that the contactor 62 engages the stationary switch contact 66 and thereby closes an electrical circuit including the wires 68 and 70, the audible buzzer

72, the light bulb 74, and the battery 76, with whose poles or terminals the wires 68 and 70 make electrical contact by means of leaf spring contacts 78, 78.

A setting lever 80 traverses the control box 52 and is pivoted at one end to a sidewall of the control box, as indicated at 82, with its opposite end 84 projecting outwardly of the box through a vertical slot 86 formed in the opposite sidewall of the box and forming a handle. The lever 80 is pivotally connected intermediate its ends to the housing 64 by means of a pin 88 whereby the housing 64 is elevated or lowered whenever the handle of the setting lever 80 is moved between different settings indicated on a depth indicator scale 90, attached to the outside of the control box 52, the handle 84 having a pin 92 capable of being inserted in any desired one of the position holes 91 of the scale 90, to hold the lever 80 and thereby the housing 64, in positions corresponding to a water shallowness at which it is desired to have the alarm operate.

The rod 40 slides through the top and bottom of the housing 64, and as shown in Figure 2, has circumscribed thereon a relatively long helical spring 94, which is compressed between an upper washer 102 engaged with the top of the housing 64 and a lower washer 98. A shorter helical spring 96 in the rod 40, is compressed between a washer 104 engaged with the bottom of the housing 64 and a washer 100 on the rod 40 below the washer 98. The short spring 96 yieldably supports the weight of the rod 40 and feeler rod 46 and counterbalances the action of the longer spring 94.

A pin 97 extending from opposite sides of the rod 40 is engaged between the washers 98 and 100, so that upon rise of the rod 40 from depressed position the spring 94 will be compressed and the spring 96 will then have the tendency to depress the rod 40 when released. By adjusting the setting of the handle 84 of the lever 80, the buzzer 72 and the lamp 74 will be operated only when shallowness corresponding to the set position has been reached, since the adjustment of the lever 80 determines the degree of water shallowness at which the switch 63 will be closed. When the pin 92 of the setting lever 80 is in any upper one of the scale holes 91 on scale 90 and the feeler 50 meets a bottom area or a water obstruction higher than that for which the lever 80 has been set, the feeler 50 is forced upwardly toward the bottom of the boat and the spring 94 yields upwardly and permits the rod 40 to rise relative to the housing 64 and operate the contactor 62 of switch 63 to closed position and thereby operate the buzzer 72 and the light bulb 74.

The handle 26 of the cap 24 is used to turn the feeler assembly 46, 50 to the desired rearward angle before placing the pin 92 in a hole 91 in the scale 90, so as to position the feeler assembly in an out of the way position against the bottom 12' of the boat 12, when not in use. The handle pointer 28 serves to show the angulation of the feeler assembly 46, 50 at all times, and with said assembly trailing freely, can show the direction in which the boat may be drifting in foggy weather, which is frequently otherwise difficult to determine under such conditions.

The spring 94 should be flexible enough to allow the rod 40 to rise freely at all times, yet stiff enough to offset upward pressure of the water against the feeler assembly 46, 50 while the boat is travelling at a rate of about five miles

per hour, which may be considered safe cruising speed in shallow water.

The entire device may also be constructed to be attached to the deck or gunwale of a boat outside the cabin, so it can be taken in and stored when not in use, such construction being useful where the owner does not desire to build it into the boat.

Although I have described a preferred embodiment of my invention in specific terms, it is to be understood that various changes may be made in sizes, shape, materials, and arrangement without departing from the spirit and scope of the invention as claimed.

15 I claim:

1. A shallow bottom alarm for a boat comprising a housing adapted for stationary mounting on the boat, a control box arranged for stationary mounting on said boat above said housing, switch means in said box comprising a stationary switch element and a movable switch element tensioned away from and normally disengaged from said stationary switch element, a vertical rod supported to move upwardly and downwardly through said housing and said control box, said rod having a portion engageable with said movable switch element only in an elevated position of said rod whereby said movable switch element is moved into engagement with said stationary switch element to close a circuit, a declining feeler arm pivoted at its elevated end to said housing and connected intermediate its ends to said rod whereby said rod is elevated from a depressed position to an elevated position to close 35 said switch means whenever the depressed end of said feeler arm encounters a bottom area subsisting at a higher level than the depressed end of said feeler arm and is raised above its normal declining position, setting means for said feeler 40 arm whereby said feeler arm may be set at different declining angles so as to operate at corresponding different degrees of bottom shallowness, said setting means comprising a setting lever pivoted at one end on said control box, 45 means operatively connecting said lever at a point intermediate its ends to said rod, said lever being swingable in a vertical plane to elevate or depress said rod and thereby change the declining angle of said feeler arm, and a depth 50 indicator scale on said box with which a portion of said lever is engageable for holding said lever in a selected set position.

2. A shallow bottom alarm for a boat comprising a housing adapted for stationary mounting on the boat, a control box arranged for stationary mounting on said boat above said housing, switch means in said box comprising a stationary switch element and a movable switch element tensioned away from and normally disengaged from 60 said stationary switch element, a vertical rod supported to move upwardly and downwardly through said housing and said control box, said rod having a portion engageable with said movable switch element only in an elevated position of said rod whereby said movable switch element is moved into engagement with said stationary switch element to close a circuit, a declining feeler arm pivoted at its elevated end to said housing and connected intermediate its ends 65 to said rod whereby said rod is elevated from a depressed position to an elevated position to close said switch means whenever the depressed end of said feeler arm encounters a bottom area subsisting at a higher level than the depressed end 70 of said feeler arm and is raised above its 75 end of said feeler arm and is raised above its

normal declining position, setting means for said feeler arm whereby said feeler arm may be set at different declining angles so as to operate at corresponding different degrees of bottom shallowness, said setting means comprising a setting lever pivoted at one end on said control box, means operatively connecting said lever at a point intermediate its ends to said rod, said lever being swingable in a vertical plane to elevate or depress said rod and thereby change the declining angle of said feeler arm, and a depth indicator scale on said box with which a portion of said lever is engageable for holding said lever in a selected set position, said connecting means comprising a rigid component carrying said switch means and movable vertically relative to said rod, a first spring component yieldably supporting the weight of said rod and said feeler arm on said rigid component, and a second spring component yieldably resisting upward movement of said rod relative to said rigid component.

3. A shallow bottom alarm for a boat comprising a housing adapted for stationary mounting on the boat, a control box arranged for stationary mounting on said boat above said housing, switch means in said box comprising a stationary switch element and a movable switch element tensioned away from and normally disengaged from said stationary switch element, a vertical rod supported to move upwardly and downwardly through said housing and said control box, said rod having a portion engageable

with said movable switch element only in an elevated position of said rod whereby said movable switch element is moved into engagement with said stationary switch element to close a circuit, a declining feeler arm pivoted at its elevated end to said housing and connected intermediate its ends to said rod whereby said rod is elevated from a depressed position to an elevated position to close said switch means whenever the depressed end of said feeler arm encounters a bottom area subsisting at a higher level than the depressed end of said feeler arm and is raised above its normal declining position, and handle means carried by said housing and connected to said rod for rotating said rod and said feeler arm into positions of different angulation with respect to the longitudinal axis of the boat.
